UNITED STATES PATENT OFFICE.

THOMAS J. KERWIN, OF CHICAGO, ILLINOIS, ASSIGNOR, BY MESNE ASSIGNMENTS, TO CHICAGO ELECTRIC MANUFACTURING COMPANY, OF CHICAGO, ILLINOIS, A CORPORATION OF ILLINOIS.

ANGLE PLUG.

Application filed January 3, 1921. Serial No. 434,733.

My invention relates to the class of electric fittings commonly known as attachment plugs and used for affording a detachable circuit connection to a socket for an electric 5 lamp or the like. Generally speaking, my invention aims to provide a cheaply constructed, strong and good looking fitting of this kind which will be easy to wire, which can readily be used to good advantage with 10 wires coming from a direction angular to the axis of the socket, which will afford strong mechanical protection as well as weather-proof protection for the point of attachment of the wire, and which will readily relieve such connection of any strain on 15 the wire.

In one of its more particular aspects, my invention aims to provide an attachment plug of this kind having a metallic casing 20 so designed as not only to house the insulating body which carries the wire terminal or terminals, but also completely to house the joint between the wire and such terminal or terminals, and having a portion of this casing disposed for relieving these terminals of any strains on the wire. Furthermore, I aim to provide exceedingly simple and effective means for attaching the wire; to provide simple means for holding the insulating 25 body which supports the wire terminal or terminals, and for permitting a ready connecting of the wires to the same; to provide a casing so arranged as to facilitate this wiring even when the wire comes from a general direction at right angles to the axis of 30 the socket with which the plug is to be used, and to provide simple means for mechanically protecting the resulting joint or connection. Moreover, my invention aims to 35 provide an attachment plug with a casing having its main portion formed from a single piece of die cast metal and having a separable cap so arranged as to take thrust off the connection to the wire, and also arranged 40 so that it can be used with equal facility with metal-sheathed wire. Still further and more detailed objects will appear from the following specification and from the accompanying drawings, in which 45

Fig. 1 is a side elevation of a single pole angle-plug embodying my invention, together with a section of the rear end of a lamp socket interlocked with this plug.

Fig. 2 is a section through the same angle plug, taken along the medial plane of the 55 angle and showing the cap of the plug as engaging a wrapping of tape on the wire.

Fig. 3 is a similar section through a double-pole angle plug, showing the cap as engaging a knot in the two wires. 60

Fig. 4 is a transverse section through Fig. 2 along the correspondingly numbered line of that figure.

Fig. 5 is a reduced section through the main metal portion of Fig. 2 showing the disposition of the wire before the same is attached to the wire terminal, and also showing this metal elbow as equipped with cross-pins at right angles to the medial plane of the angle plug. 70

Fig. 6 is a fragmentary horizontal section taken along the line 6—6 of Fig. 2.

Fig. 7 is a perspective view of the wire terminal.

Where the wire or wires which are to connect to an attachment plug come from a direction substantially at right angles to the axis of the socket with which the plug is to be used, it has heretofore been customary to construct angle plugs (sometimes also known as elbow plugs) with the wire terminal and contact terminal portions carried by a tubular elbow molded of insulating material and to conceal the attachment of the wire or wires by a cap threaded upon this insulating body. Owing to the nature of the insulating compounds generally used for such purposes, the resulting plugs have proven too brittle to stand knocks, and too easily softened to retain a firm grip in hot weather on the imbedded pins which interlock such plugs with the lamp sockets. Nor has the angular shape of the insulation lent itself to the employment of a metal shell such as would be highly desirable where 85 fittings of this kind are likely to be subjected to rough treatment, as in the case of connector plugs for use with the electric head lamps on Ford automobiles. Moreover, the attaching of a wire within a tubular elbow is difficult to perform with the proper firmness for preventing a strain on the wire from severing the connection or possibly rupturing the wire at its point of attachment. 100

To overcome all of these difficulties, my

invention aims to provide connector plugs employing tubular metal elbows which will afford the desired mechanical protection, and to provide an elbow-shaped metal casting which can readily be made of a die casting; to provide the insulating portion in a relatively small form which can readily be machined out of hard rubber, thereby permitting of a less fragile form of insulation than that ordinarily obtainable in a molded composition; to provide a simple and inexpensive form of wire terminal which can readily be attached to such a cheaply manufactured insulating part and which will effectively anchor the wire without appreciably weakening the latter; to arrange the parts so that the wire can readily be attached to the terminal while the latter is disposed outside of the tubular elbow; to provide simple means for causing a retraction of the wire to seat the insulating body firmly in the elbow; and to provide simple and effective means for preventing an excessive retraction of the wire after it has thus drawn the insulator to its seated position. Furthermore, my invention aims to provide a connector plug of the class described which will readily lend itself to both single-pole and double-pole constructions and which will readily predetermine the medial plane of the elbow when the plug is in use.

In their immediate commercial aspects, the connector plugs of my invention are particularly suited for use in connection with automobile lamps carried by sockets having their shells equipped for interlocking with laterally projecting pins on the plugs and having spring-pressed contact elements adapted to engage the wire terminals on the plugs when the latter are thus interlocked with the shells of the sockets. I am therefore illustrating and describing the connector plugs of my invention in forms adapted for these purposes, although I do not wish to be limited to any particular uses of the same.

Referring first to the connector plug of Figs. 1, 2 and 4, these figures show an angle plug designed for use with a lamp socket having a cylindrical shell 1 equipped near its end with diametrically opposite bayonet slots adapted to engage lateral pins 2 projecting from the angle plug. The socket shell 1 houses the usual insulating body 3 supporting a spring-pressed plunger 4 which is disposed axially of the casing 1 and is continuously urged by the spring associated with it towards the rear end of the socket shell, after the general manner of the plunger shown in U. S. Patent No. 1,083,542 of January 6, 1914 to George C. Knauff. To cooperate with the plunger 4 which forms parts of the connection within the socket to the lamp, I provide a screw 5

which extends through an axial bore in a cylindrical insulator 6 and which is threaded into the shank 7 of a wire terminal equipped at its rear end with a loop 8 through which the tip portion of the corresponding wire 9 is adapted to be hooked. The threaded shank 7 of the wire terminal is slidably disposed in a bore of larger diameter than the shank of the screw 5 and extending into the insulator 6 from the rear of the latter, so that upon tightening the screw 5 the shank 7 will be drawn forwardly of the insulator and will therefore double the tip 9 of the wire into a loop and draw this tip into the bore 10 within which the shank 7 is slidably disposed. In so doing, the screw kinks the wire into an anchoring loop before the tip of the screw engages the wire and clamps the latter against the rear part of the loop 8.

The insulator 6 in turn is merely slidable in the forward end of the metal elbow 11, which elbow is desirably of die-cast metal and desirably has the anchoring pins 2 cast upon the same. This elbow has its bore contracted to form an interior annular shoulder 13 spaced from the forward end of the elbow by a distance shorter than the length of the insulator 6, so that the entry of this insulator into the elbow will be limited by this shoulder to a position in which the forward end portion of the insulator 6 projects beyond the forward end of the elbow. Moreover, the metal elbow also desirably has integral with it a web 14 extending longitudinally along its interior for some distance forward of the said shoulder 13 and adapted to enter a corresponding longitudinal recess on the surface of the insulator 6 after the manner shown in Figs. 2 and 4, so as to prevent the insulator from rotating within the bore of the elbow. The rear end of the elbow, which end in the illustrated embodiment extends at right angles to the forward end, desirably is threaded on its exterior to fit a cap 15 for the purposes hereafter described.

With the parts thus arranged, the cap 15 is first left off the elbow but slipped over the free end of the wire, while the insulator 6 together with the wire terminal carried by the latter are left out of the metal elbow. Then the wire 11 is slid through this elbow after the manner shown in Fig. 3, which can readily be done while imparting a relatively slight curve to the wire, and this wire is attached to the wire terminal after the manner shown in Fig. 2. Then the wire is pulled back, and the insulator 6 is slid into the forward end of the metal elbow during this retracting of the wire until the insulator engages both the web 14 and the annular shoulder 13. After this has been done, the cap 15 can be brought up from its previous loose position of Fig. 5 and can readily be

screwed upon the rear end of the elbow so as to afford a handsome finish for this end, while also providing means for securing the metal of the elbow tightly to a metal sheath 5 16 on the wire if the wire was metal sheathed. In either case, I also desirably employ this cap for relieving the wire of any strains which might tend to pull its tip out of the fastening of the latter to the 10 wire terminal, such as a downward pull on the wire in Fig. 2. For this purpose, I may simply wrap the wire adjacent to the rear end of the elbow with a few layers of tape 17, thereby providing an enlargement of 15 greater diameter than that of the bore of the cap 15, so that the contracted tail end of this cap will engage the tape when the cap is screwed into position (as shown in Fig. 2) and thereby will relieve the wire of undue 20 strains.

With the parts thus arranged and assembled, it will be obvious that the metal shell of the installed plug will afford a strong mechanical protection; that the general arrangement will facilitate the wiring, and that the ability to attach the wire to this terminal while the latter is out of the elbow will insure the making of a connection which will be both mechanically and electrically 25 ample. Moreover, the position of the anchoring pins 2 with respect to the medial plane of the elbow will readily determine the position of the plug when used in connection with a lamp-socket having bayonet 30 catch formations in any given position. For example, if the socket has its axis horizontal and has its bayonet catch formations in a 35 vertical plane through that axis, and the angle plug having its anchoring pins in the medial plane of the elbow will present its 40 rear end in a vertical position after the manner of Fig. 1.

However, while I have heretofore described the connector plug of my invention 45 in a single-pole embodiment and have illustrated the same as including a right-angled elbow, I do not wish to be limited to these or other details of the construction and ar-

rangement thus disclosed, it being obvious that the same might be modified in many 50 ways without departing from the spirit of my invention. For example, a two-wire plug can readily be constructed in the same manner by equipping the insulator 6 with two wire terminals as illustrated in Fig. 5, in 55 which case the cap 15 might engage a knot in the two wires instead of the tape of Fig. 2. So also, the relative position of the cross-pins 2 might be altered, as for example after the manner indicated in dotted lines in Fig. 60 3 which shows an elbow designed for use at right angles to the position of Fig. 1.

I claim as my invention:

In an electric fitting, an elbow-shaped casing having its forward arm counterbored to 65 provide an inner annular shoulder spaced from the mouth of the said arm and having a fin projecting radially inward into the said counterbored portion adjacent to the said shoulder, the shoulder being disposed forwardly of the bend of the casing; a tubular insulator socketed in the said counterbored arm and abutting at its rear end against the 70 said shoulder and having a notch fitted over the said fin to prevent the insulator from 75 rotating in the said arm, the forward part of the bore of the insulator being contracted in diameter; a wire terminal member slidably inserted in the insulator bore from the rear 80 of the insulator and having a forward threaded end and presenting an eye adjacent to the rear end of the insulator; a screw extending through the contracted bore portion 85 of the insulator and having its head engaging the forward end of the insulator and its shank threaded into the said threaded end of the wire terminal member; and an insulated circuit wire extending into the casing 90 through the other arm of the casing and having a bared end extending through the eye of the terminal member and clamped against and kinked into the rear end of the insulator bore.

Signed at Chicago, Illinois, December 23rd, 1920.

THOMAS J. KERWIN.
